United States Patent Office

Des. 193,866
Patented Oct. 16, 1962

193,866

BEARING

Frank H. Sully, % Western Brass Works,
1440 N. Spring St., Los Angeles, Calif.

Filed Jan. 18, 1960, Ser. No. 59,090

Term of patent 3½ years

(Cl. D46—1)

FIG. 1.

FIG. 2.

FIG. 1 is a perspective view of a bearing showing the front end, top and one side of my new design.

FIG. 2 is a perspective view showing the rear end, bottom and other sides thereof.

I claim:

The ornamental design for a bearing, as shown.
